**ELECTRIC BELL HAVING HINGED MOVEMENT
ABOUT HANGER HOOK**
Harold E. Seaton, Shelby, Ohio, assignor to The Autocall
Company, Shelby, Ohio, a corporation of Ohio
Filed Dec. 20, 1965, Ser. No. 514,791
16 Claims. (Cl. 340—396)

ABSTRACT OF THE DISCLOSURE

A large electric bell of the fire, school or industrial variety is disclosed. The bell is hinged at the top of the mounting plate and the gong encloses the striker mechanism.

The present invention relates to electric bells, such as fire bells, school bells, industrial bells and the like. As is well known in the art, these electric bell assemblies comprise solenoids or like electromagnetic devices, together with plunger or striker units responsive thereto for striking the bells.

One of the features of the invention is the provision of a new and improved construction of carrier element for carrying the solenoid and also carrying the plunger. In this regard, another feature of the construction is a new and improved mounting or guiding rib means and associated numerical scale for adjusting the solenoid and plunger assembly relatively to the gong for adjusting the loudness or tone of the gong, and also for adjusting for different sizes of gongs; as will be later described in greater detail.

Another feature of the invention is the provision of a new and improved construction and location of locking mechanism which makes it impossible for the housing and gong to become accidentally loosened from the rearwardly disposed anchorage plate which carries the housing and gong. Many large size gongs create relatively severe vibration during their sounding operation, and instances have occurred in which the housing and gong have become loosened and have fallen from elevated positions, with resultant serious damage.

Another feature is the provision of new and improved constructions which can operate under alternating current energization, or under direct current energization.

Another feature is a new and improved construction of alternating current bell which utilizes a permanent magnet in its operation. The invention also provides an alternating current bell which does not utilize a permanent magnet in its operation.

Another feature is a new and improved construction of single stroke alternating current bell which will sound only one stroke when the bell is energized. Another feature characterizing this single stroke alternating current bell is that this bell will give this single stroke performance irrespective of whether the bell is mounted with the plunger facing horizontally, vertically, obliquely, or at any other angle.

Another feature is an improved construction which is rainproof, snowproof and moisture-proof. This is attained by a unique relation of rubber sealing ring which is secured within the housing and is adapted to have pressure abutment against the outer face of the rear anchorage plate.

Another feature, briefly referred to above, is the improved construction and arrangement wherein numerous different types of solenoid carriers and plungers can be substituted in guiding ribs which are standardized in each mounting housing, so that different carriers can be substituted in the same or different housings. In this regard, a further feature resides in the provision of a numerical scale along one of the guide ribs for cooperating with a

2

data mark on the solenoid carrier for indicating when the solenoid carrier is at the same marking, or at some chosen different marking in the mounting housing. All of the corresponding solenoid carriers have the same data marking, and all of the corresponding mounting housings have the same numerical scale for assuring identity of setting. This arrangement facilitates the assembly of the bells in an assembly line operation, after the desired number on the numerical scale has been chosen.

10 Another object is to provide a construction which can be readily opened for inspection and repair.

Another object is to provide a construction which is simple and inexpensive, both with respect to cost of the parts and assembly of the parts.

15 Other objects, features and advantages of the invention will be apparent from the following detailed description of preferred embodiments thereof.

In such embodiments:

FIGURE 1 is a front elevational view of an entire bell assembly, on a reduced scale;

20 FIGURE 2 is a rear elevational view of the same, on the same reduced scale;

FIGURE 3 is a front elevational view of the mounting plate, on a larger scale, with the housing removed therefrom;

25 FIGURE 4 is a vertical sectional view of the mounting plate taken approximately on the plane of the line 4—4 of FIGURE 3;

30 FIGURE 5 is a detail sectional view of one of the receptor terminal blocks on the mounting plate, taken on the plane of the line 5—5 of FIGURE 3;

FIGURE 5A is a view similar to FIGURE 5, but showing one of the prong terminal blocks which are mounted on the housing;

35 FIGURE 6 is a rear elevational view of the housing viewed from the rear side, before the prong terminal blocks and the slidably solenoid and striker unit have been assembled thereon;

FIGURE 7 is a fragmentary view of this same part of the housing, but with the prong terminals and the solenoid and striker unit assembled thereon;

FIGURE 8 is a vertical diametrical sectional view through a complete bell assembly of the vibratory alternating current permanent magnet type;

45 FIGURE 9 is a detail sectional view of the solenoid and plunger unit of FIGURE 9, but on a larger scale of about twice that of FIGURE 8;

FIGURE 10 is a fragmentary sectional view, similar to FIGURE 9, but illustrating a single stroke bell, adapted 50 for either direct current operation or alternating current operation;

FIGURE 11 is another view similar to FIGURE 9, but illustrating a vibratory direct current make-and-break bell, 55 wherein the bell makes and breaks its own direct current circuit for continuous vibratory operation.

The entire bell assembly (FIGURE 8) comprises three main elements, to wit; the front gong 20, the housing 21 and the mounting plate 22. The gong is secured to the housing 21, the housing 21 is secured to the mounting plate 22 and the mounting plate 22 is secured to any standard back box or to any suitable part of the building structure or other appropriate support.

Referring first to the details of the mounting plate 22, this comprises a circular disk-like stamping or die casting 65 having a recessed web portion 24 (FIGURES 3 and 4) from which flares an inclined flange 26, and from which then projects a radially extending flange 27. The web portion 24 is provided with a plurality of perforations 29 to facilitate the different placing of bolts or screws entering the back box or main support, and also for providing mounting tabs for mounting the terminal blocks, as will

be later described. The electrical conductors enter through a central hole 31 in the mounting plate 22 for connecting with these terminal blocks. The top and bottom mid-points of the flange 27 are established on a diametrical arbitrary line X—X which passes midway between the vertical, parallel positioning of the two receptor terminal blocks 33, 33. At the top of the flange 27 is formed a safety hanger bracket 35 having notched-out ends 36. On the diametrically opposite side of the flange 27 is cut a notch 38 for receiving a locking screw carried by the housing. The manner in which the hanger tab 35 and notch 38 cooperate in providing a safety hanger support for the housing will be later described after the description of the housing.

Referring now to the receptor terminal blocks 33, these are of long, narrow form spaced equidistantly outwardly from the conductor hole 31 and running parallel to the diametrical line X—X extending centrally through the hanger tab 35 and locking notch 38. These terminal blocks 33 have slotted end lugs 41 into which extend crimping lugs 42 punched out of the web 24, and pressed firmly into the slotted lugs 41 (FIGURE 5). Punching the crimping lugs 42 out of the web 24 leaves holes 40 in the web into which fit downwardly projecting lugs 40' molded from the bottom of the insulating terminal block 33. Threaded sleeves 43 are inserted into elevated portions of each block at the time the blocks are molded (FIGURE 5), and terminal screws 44 thread into these threaded sleeves for establishing electrical connection with the conductors entering the device. A metallic clip 46 is secured to threaded sleeve 43 by swedging, and is formed with forwardly and upwardly shaped terminal lips 47, between which the other prong terminal associated with the housing is adapted to enter.

Referring now to the housing 21, this is preferably formed of a nonmagnetic material, and has the sectional configuration best shown in FIGURE 8. This housing 21 has an outer rim 51 from which extends an inwardly curved portion 52, which, in turn, joins with a cylindrical socket 55 projecting forwardly into the bell 20, this socket having a flat bottom wall 57. This floor portion is formed with a threaded central boss 58 into which threads a bolt or screw 59 which serves to fasten the center of bell 20 to the housing 21.

Referring now to the top hanger bracket mounting of the top of the housing 21 to the top of the mounting plate 22, it will be seen from FIGURE 8 that the outer flange 51 of the housing 21 has substantial width and depth. At the top central portion of this flange is formed an upwardly and forwardly extending arcuate slot 61 of a width just slightly more than the width or length of the interlocking lug 35 on the mounting plate 22. The forward edge of the slot 61 has a slight slope 62 in a forward direction to facilitate the movement of the slot 61 over the hanger bracket 35 in the assembling operation. When the parts are properly centered with the interlocking lug 35 uppermost, the housing 21 can thereupon be drawn downwardly with the lug or tab 35 moving upwardly within the slot 61 formed in the top of the housing. This enables the lower part of the housing 21 to bring the lower part of flange 51 of the housing over the lower peripheral portion of the mounting plate 27. Screwing upwardly through the bottom part of the flange 51 is an interlocking screw 64 which is adapted to pass through the notch 38 when the housing is being swung to a closed position. This brings the screw 64 into contact with or slightly beyond the peripheral flange 27, whereupon the screw 64 may be threaded upwardly to establish an interlocking relation against the back side of the flange 27 for securely fastening the housing 21 to the mounting plate 22. This mounting of the housing 21 on the mounting plate 22 prevents any possibility of the housing and gong assembly from vibrating loose from the mounting plate 22. To vibrate loose, the hanger would have to vibrate in an upward direction, and the screw 64 prevents

this. A rubber sealing ring is partially embedded in the outer flange 51 of the cover 21 and is adapted to have sealing abutment against the front face of flange 27 of mounting plate 22. This substantially excludes rain, snow and the like from entering the interior of the bell housing through the joint between the housing 21 and the mounting plate 22.

Referring now to the prong type of plug-in terminals 69, these are mounted in the socket 55 for plug-in reception in the receptor terminals 33 when the housing is swung into closed position around the interlocking lug 35 acting as a hinge. Each prong terminal is moulded into one end of a relatively long narrow insulating block 73. Passing through the other end of the block is a screw 74 which screws into a threaded hole 76 in a substantially square lug 76' projecting up from the bottom wall of the socket 55 for anchoring the terminal block. Parallel longitudinal lugs 77 and a transverse end lug 78 extend upwardly from the bottom wall 57 of the socket 55 and define a pocket for anchoring each terminal block. Locating the plug-in terminals at the bottom of the socket 55 places the outer ends of the plug-in terminals below the level of the top edge of the flange 51, where they will be protected from injury.

The solenoid striker unit 70 is mounted for vertically adjustable sliding movement in a vertical guideway 79 defined between upper and lower pairs of guide ribs 80 and 81 which project integrally upwardly from the floor 57 of the socket 55 (see FIGURES 6 and 7). The solenoid unit can be locked in any desired shifted position by locking screws which will be later described. Of these guide ribs, the lower left-hand rib, designated 81', is made slightly wider than the others for receiving a numbered scale 83. Embossed, or otherwise marked, on this rib 81' is the numbered scale 83 bearing numbers such as 1, 2, 3, etc. The lower left-hand corner 84 of the shiftable solenoid unit constitutes the data or reference point which is read against the numbered scale 83, for determining the adjusted position of the solenoid unit. Between the upper guide ribs 81 is a lower bearing rib 86, and between the two lower ribs 81, 81' are two lower bearing ribs 87, each integral with the bottom wall 57. These bearing ribs 86 and 87 are formed slightly lower than the guide ribs 80 and 81, and afford a smooth slide surface constituting part of the vertical guideway 79 for slidably supporting the solenoid unit 70.

Referring now to the construction of this solenoid unit 70, it comprises a solenoid coil 91 which is assembled in a solenoid frame 92. This frame is preferably in the form of a U-shaped stamping of magnetic metal comprising a back bridging portion 93, from the top and bottom ends of which extend parallel top and bottom leg portions 94 and 95 (FIGURE 8). Bent at a right angle from the inner edge of the upper leg 94 is an anchoring flange 97 having parallel vertical slots 98 formed therein. Anchoring screws 99 pass through these slots and thread into tapped holes 102 in the bottom wall 57 of the socket 55. The slotted flange 97 has sliding guided engagement between the upper guide ribs 80, and the lower flange 95 has sliding guided engagement between the lower guide ribs 81; although this upper and lower relationship may be reversed, if desired. It will be understood that loosening of the anchoring screws 99 will permit the upward or downward shifting of the solenoid operating unit to any position desired. Flexible conductors 103 extend from the sides of the solenoid coil and have their ends soldered to the base portions of the prong terminals 69, these flexible wires accommodating the aforesaid sliding movement of the solenoid operating unit.

Extending approximately halfway in the solenoid winding 92 is a guide tube 104 composed of a non-magnetic metal, such as beryllium copper, or the like. This guide tube extends downwardly through a hole in lower leg 95 and also through a hole 106 in the socket portion 55 of the housing 21. Reciprocating freely in this guide tube

104 is a plunger 108 comprising a magnetic upper portion 109 and a non-magnetic striker portion 111, which is adapted to strike the bell 20. Coextensive with the upper end of the non-magnetic guide sleeve 104 is a tubular magnetic pole piece 114 having a depending lower sleeve 115 in which is inserted a compression spring 117. The lower end of this compression spring encircles a centering pin 118 projecting upwardly from the plunger 108. Screwing into a threaded bore 119 in the upper end of the magnetic pole piece 114 is a non-magnetic brass screw 121 which holds the pole piece fixedly in position.

The lower end of the solenoid coil seats directly on the lower frame leg 95 of the solenoid frame. Seating on the top surface of the solenoid winding is a magnetic pole plate 123 which is preferably in the form of a rectangular iron plate of high magnetic permeability. The retaining screw 121 passes down through a central hole in this pole plate.

Interposed between this pole plate and the upper leg 94 of the solenoid frame is a powerful permanent magnet 125 preferably in the form of a rectangular flat plate having approximately the perimeter dimensions of the pole plate 123. Although the body of this magnet may be composed of Alnico, ceramic, plastic or other suitable materials, I preferably construct the magnet of rubber permeated with magnetizable materials. The top portion of this magnet is of one magnetic polarity and the bottom portion is of the opposite polarity. Solely for facility of description, let it be assumed that the top portion is of south polarity and the bottom portion is of north polarity. Under these conditions, the north pole flux from the bottom of the magnet will permeate the pole plate 123 and the pole bushing 114. Conversely, the south flux from the upper side of the permanent magnet will permeate the entire solenoid frame, including the top leg 94, bridging member 93 and also the bottom leg 95. Also, the magnetizable upper portion 109 of the reciprocating plunger 108 will assume south pole magnetization because of its proximity to the south pole flux in the lower leg 95 of the solenoid frame. The permanent magnet 125 is preliminarily magnetized either to or approximately to the saturation point, prior to assembly in the bell.

Referring now to the operation of this embodiment, when the solenoid coil is deenergized, the direction of the pull exerted on the plunger is in an upward direction, owing to the pull of the permanent magnet 125 overcoming the weight of the plunger, the downward thrust of the spring 117, etc. Thus, the plunger 108 is held in a neutral position between compression position and operated position. After an electrical operation, the plunger will always return to this neutral position. It will be understood that the poles of the permanent magnet remain constant, while the coil alternately reverses the poles on each $\frac{1}{2}$ cycle of a sine wave. Let us assume that on the upward alternation of the current, the solenoid coil and the permanent magnet combine their magnetic lines of force and aid each other in establishing a magnetic pull. The combined magnetic lines of force from the coil and from the permanent magnet increase the pull on the plunger and cause a compression of the compression spring 117 which pulls the plunger away from the gong. On the next or downward alternation in the alternating current, the direction of plunger travel reverses when the solenoid energizes on this $\frac{1}{2}$ cycle. The solenoid coil reverses poles, and the coil and permanent magnet then buck each other and cancel substantially all the magnetic lines of force. The sudden release of the plunger from the previous magnetic pull causes the compressed spring 117 to shoot the plunger against the gong with substantial impact.

In FIGURE 10, I have illustrated the substitution of a single stroke striker mechanism in the bell assembly, in lieu of the continuously vibrating striker mechanism just described. This single stroke embodiment is operable on either direct current or alternating current; and is

operable when the bell is mounted at any angle; i.e. with the plunger reciprocating either vertically, horizontally or at any intermediate angle. For facility of description, it will be assumed that the installation is vertical with the plunger being projected downwardly to make its single stroke impact against the gong. In this embodiment, the upper end of the non-magnetic guide tube 104a projects substantially above the upper leg 94 of the solenoid frame. This upper end is closed by crimping the end of the tube, and, if desired, a cushioning pad 127 may be inserted in this closed end. The lower end of the guide tube also extends a substantial distance below the solenoid frame, and this end has a slightly inwardly curved lip 128. The plunger 130 has a long relatively thick body portion 131, and also has a slender gong striking extension 132. The main body portion 131 is composed of iron or other magnetically responsive material, and the gong striking extension 132 is composed of non-magnetic material. A shoulder 134 is defined at the juncture between the thick and thin portions of the plunger. A long conically-shaped compression spring 135 has its small end abutting this shoulder 134 and has its large end abutting the inwardly curved lip 128 at the lower end of the guide tube. This spring has just enough compression strength to sustain the weight of the plunger so that the plunger is normally held in the elevated position shown. When the solenoid is energized, the magnetic flux therefrom operates to draw the magnetic body portion 131 of the plunger down into a central position with respect to the solenoid coil, thereby causing the striker pin 132 to move out of the guide tube and to strike the gong with a sharp impact blow. This gives the bell its single stroke operating characteristic. Obviously, when energized by direct current, the plunger remains in its gong striking position; and when energized by alternating current, the frequency of alternations exceeds the responsiveness of the relatively heavy plunger, and, hence, the plunger remains in its single stroke position in contact with the gong. In this single stroke embodiment, the entire solenoid striker unit can, of course, be adjusted to different back or forth positions between the guide ribs 80, 81, etc. Also, in substantially all other respects this single stroke embodiment corresponds to the previously described embodiment, including the hanger bracket 35, the adjustability between the guide ribs 80-81, etc.

Referring now to the vibratory direct current embodiment which makes and breaks its own circuit, this embodiment is best shown in FIGURE 11. The solenoid striker unit is very similar to the preceding embodiments, having the same to-and-fro adjusting movement between the guide ribs 80-81 in conjunction with the numerical scale 83. Mounted on the back bridging wall of the solenoid frame is an adjustable extension plate 140 which has adjusting slots 141 therein for receiving screws 142 which thread down into tapped holes in the solenoid frame. This arrangement of slots and screws enables the plate 140 to be adjusted for adjusting the position of the direct current switch. Projecting from the plate 140 is an arm 145 having a forwardly bent mounting lug 146. Secured to the face of this lug by screws 148, threading into the lug, is a small make-and-break switch 150, comparable to a micro switch. The enclosed contacts are actuated by a thin flexible actuating arm 152 which projects from the switch housing into the path of the solenoid actuated plunger 130. The two switch contacts of this switch are interposed in series between one of the terminal prongs 69 and the adjacent end of the solenoid winding. This plunger may be a substantial duplicate of the above-described plunger shown in FIGURE 10. That is to say, it may comprise the relatively thick magnetic portion, having the bell striking non-magnetic tip at its outer end, surrounded by a conically wound compression spring 135a, similar to the spring 135. Normally, this conical spring will maintain the plunger in the retracted position shown, wherein the large end of the plunger bears against

the switch actuating arm 152 for holding the switch in closed position. When energizing current is supplied to the bell assembly, the resulting energizaiton of the solenoid attracts the plunger outwardly and causes its striker tip to strike the gong. This outward movement of the plunger opens the switch 150, thereby immediately de-energizing the solenoid 92 so that the reaction of the plunger closes the switch again. This immediately sounds the bell again, which keeps on continuously as long as current is supplied to the solenoid. Here again, this embodiment has the hanger bracket 35, the adjustability between the guide ribs 80-81, the side location of the terminal blocks 33, 69, etc.

It will be seen that in each of the embodiments shown, the solenoid winding has its long dimension extending vertically so as to reduce the horizontal width or breadth of this part of the assembly. Also, the location of the slotted anchoring flange 97 extending vertically, and the vertical location of the slide guideway 79 between the guide ribs 80, 81 under the solenoid frame, further reduce the breadth of the assembly. Moreover, the location of the permanent magnet on the vertical axis of the solenoid reduces the horizontal dimension. Still further, the location of the terminal blocks 33 and 73 in close proximity to the solenoid frame keeps the breadth down considerably in situations where this is desirable. This is desirable when mounting the smaller gongs on the housing, such as the 4-inch or 6-inch bells. The relatively small diameter of the cup-shaped socket 55 enables this socket to be extended into or nested wthin the bowl curvature of a 4-inch gong, as clearly shown in FIGURE 8.

Referring to FIGURES 10 and 11, I have shown the guide tube 104 or 104a as being provided with upper and lower stop lugs 155 and 156 which are punched out of the body of the guide tube. The upper stop lug 155 projects outwardly above the top leg portion 94 of the solenoid frame 92, and the lower stop lug 156 projects outwardly below the lower leg portion 95 of such frame. Thus, in each embodiment the guide tube is held against upward or downward sliding movement within the solenoid and solenoid frame. The guide tube is initially punched out of flat stock, at which time the stop lugs 155 and 156 are also punched out; following which this flat blank is then curled into the cylindrical form shown. After insertion of the cylindrical guide tube through the solenoid and solenoid frame, the lugs 155, 156 are thereupon sprung outwardly into the positions shown. Removal of the tube is effected by merely bending the lugs back inwardly.

The large lettering and the prominence given to the word "TOP" at the top of the mounting plate 22 are imperative instructions that this part of the mounting plate must be located at the top. Such mounting guarantees that the housing and bell cannot be shaken loose and fall, with possible damage to persons or articles situated below.

While I have illustrated and described what I regard to be the preferred embodiments of the invention, nevertheless, it will be understood that such is merely exemplary, and that numerous modifications and rearrangements may be made therein without departing from the essence of the invention.

I claim:

1. In an electrical bell, the combination of a rear mounting plate adapted to be secured to a point of support, a hanger hook projecting upwardly from the upper portion of said mounting plate, a bowl-shaped housing having an open rear side facing said mounting plate, a hanger slot in the upper portion of said housing adapted to fit down over said hanger hook to afford a hinged hanger mounting of the housing at said hanger slot permitting hinging movement of the lower portion of said housing in an outward direction away from said mount-

ing plate, said housing having a cup-shaped socket recessed into the bottom of its bowl shape, a pair of vertically extending guide ribs formed in said socket, a solenoid operating unit mounted for slidable adjusting movement along said guide ribs, said solenoid operating unit comprising a solenoid winding, a solenoid frame carrying said winding, a guide tube extending axially of said winding, a plunger reciprocably mounted in said guide tube and having an impinging end adapted to strike a gong, and attaching means for detachably mounting said gong on said housing whereby different sizes of gongs can be substituted by said attaching means, each of said gongs substantially enveloping the major portion of said housing.

5 15. The combination defined in claim 1 wherein a permanent magnet is associated with said solenoid winding so as to have its flux interact therewith.

10 16. The combination defined in claim 1 wherein a solenoid frame carries said solenoid winding, and wherein a planar form of permanent magnet is carried by said frame at one end of said solenoid.

15 17. The combination defined in claim 1 wherein said mounting plate is provided with a designation which designates the top of said mounting plate for insuring that such portion will be mounted uppermost.

20 18. The combination defined in claim 1 wherein said mounting plate and said housing are both provided with cooperating prong and receptor terminals extending parallel with and disposed in relatively close proximity to said vertically extending guide ribs.

25 19. The combination defined in claim 1 wherein a compression spring in said guide tube acts on said plunger to cause said bell to have single stroke operation when energized.

30 20. The combination defined in claim 1 wherein a switch is made responsive to the reciprocation of said plunger to make and break the circuit of said solenoid for producing a vibratory direct current bell.

35 21. The combination defined in claim 1 wherein an indicating scale is associated with said solenoid operating unit for indicating the position to which said solenoid operating unit has been adjusted along said guide ribs.

40 22. The combination defined in claim 1 wherein a hanger tongue projects from the top portion of said mounting plate, and a hanger slot is formed in the top portion of said housing for receiving said hanger tongue.

45 23. The combination defined in claim 1 wherein a notch is formed in the lower portion of said mounting plate to clear a vertically extending screw threading upwardly through the bottom portion of said housing, whereby said screw when threaded upwardly upon the closing of said housing engages the backside of said mounting plate to hold the lower portion of said housing against outward swinging movement.

50 24. The combination defined in claim 1 wherein a permanent magnet acts on said plunger, and wherein a spring in said guide tube also acts on said plunger.

55 25. The combination defined in claim 1 wherein prong and receptor terminals are mounted on said rear mounting plate and on said housing, and wherein anchoring lugs are punched out of said rear mounting plate and are crimped over against one of said terminals to anchor it in place.

60 26. The combination defined in claim 1 wherein a slotted anchoring flange extends from one end of said solenoid frame, and a screw passes through said slot and threads into a tapped hole in said housing between said guide ribs to anchor said solenoid operating unit in any desired position of adjustment.

65 27. The combination defined in claim 1 wherein a pliable sealing gasket is secured to the rear face of said housing for establishing weather tight contact against the front face of said mounting plate.

15. The combination defined in claim 1 wherein a compression spring in the upper portion of said guide tube normally tends to force said plunger downwardly, a permanent magnet above said guide tube, and a tubular magnetic pole piece.

16. The combination recited in claim 1 wherein said

guide tube has spaced stop lugs adapted to engage said solenoid frame to retain said guide tube therein.
